UNITED STATES PATENT OFFICE.

BERNARD HAUSMAN, OF NEW YORK, N. Y.

WINDOW.

Application filed October 17, 1921. Serial No. 508,078.

To all whom it may concern:

Be it known that I, BERNARD HAUSMAN, a citizen of the United States, and a resident of the borough of Manhattan, of the city of New York, in the State of New York, have invented certain new and useful Improvements in Windows, of which the following is a specification, reference being had to the accompanying drawings, forming a 10 part hereof.

This invention relates to windows of the type known as double-hung, such as that shown in Letters Patent of the United States No. 1,331,342, dated February 17, 15 1920, in which the sash or each sash is arranged to slide vertically and is also arranged to swing inward on a horizontal axis for the purpose of permitting ventilation without draft and also of permitting ready 20 access to both sides of the window, from within, for the purpose of cleaning. The purpose of the present invention is to improve generally the construction shown and described in the Letters Patent above mentioned, and more particularly to adapt the sash supporting and locking device to metal 25 construction, to provide for the concealment of the sash chains by which each sash is connected to the counter balancing sash weights, to provide means whereby the sash 30 weights, of the usual square cross section, may be hung so as to travel in a plane parallel with the sash and to provide means whereby the sash shall be locked by its own 35 swinging movement against vertical movement. Other features of the invention will be explained more fully hereinafter with reference to the accompanying drawings in which the invention is illustrated as embodied in suitable form in connection with 40 a window of usual construction and in which—

Figure 1 is a view in front elevation, from within, of so much of the lower sash, upper sash and jamb of the window frame as is necessary to enable the application of the invention to be understood, the sash weight and chain being shown in dotted lines while the lower sash is represented in its closed 45 position.

Figure 2 is a view of the same in vertical section, as seen from the right hand in Figure 1.

Figure 3 is a view similar to Figure 2, 50 but showing the lower sash swung inwardly.

Figure 4 is a detail view in horizontal section on the plane indicated by the broken line 4—4 of Figure 1.

Figures 5 and 6 are detail views of the connection between the sash chain and the 60 swinging arm or link.

Figures 7 and 8 are detail views showing particularly the latch and the stop for the lower sash.

Figures 9, 10 and 11 are detail views of the 65 connection between the lower end of the swinging link or arm and the sash.

The improvements are shown and described as applied to the lower sash only, but it will be understood that they might be 70 applied also to the upper sash as well of a window which has two sliding sashes, upper and lower.

Except as hereinafter indicated the 75 weight box *a* may be of any usual or preferred construction, adapted for the reception and vertical movement of the two sash weights *b* and *b'* of the usual square cross section. Only one such box is shown in the drawings, but it will be understood that the 80 box at the other side of the window is similar in all respects to that shown. In the construction illustrated, three sides of the box and parts of the fourth side are formed by a continuous sheet of metal bent to meet 85 the requirements of construction and to accommodate the sash weights as described. The fourth side is completed by a face plate *a'*, which is secured at its edges to the body 90 of the box, as by screws *a''*. The plate *a'* is 95 bent to form a recess *a³*, in which are received the projecting flange of the upper sash *c*, and a weather strip *a⁴*, secured to the plate *a'* by screws, as at *a⁵*, and also to form another vertical recess *a⁶* to receive the guide 100 roller and horizontal pivot *c'* of the lower sash *c²*. The plate *a'* is also slotted vertically from a point slightly below the top rail of the lower sash when closed, to a point slightly below the head of the window 105 frame or made in two parts spaced apart.

The sash in connection with which the invention is illustrated, in this instance the lower sash, has secured to it, at each side, and at a point determined by the angle 110 which the sash is to have, a bracket *c³* which projects inwardly far enough to bring its center into the same plane with the axes of the corresponding sash weights *b*, only one of which is shown. The bracket

et c^3 forms a part of the pivotal connection between the sash and the swinging arm or link d . This pivotal connection is so designed as to assist in holding the window in position when it has been swung inward on a horizontal axis. It comprises a socket c^4 , formed with the bracket c^3 , a headed stud d' , secured to the arm d , and a stiff spiral spring d^2 interposed between the head d^3 of the stud d' and the closed end c^5 of the socket or cup c^4 . The end c^5 of the socket c^4 is dished slightly in a vertical direction or has a shallow vertical groove formed therein for cooperation with the shallow cam d^4 formed on the adjacent side of the arm d . When the arm d and the sash c^2 are in the same vertical plane, as in Figures 1 and 2, the cam surface of the arm d rests in the shallow groove or cam depression in the end of the socket and the spring d^2 is then not under compression, but when the sash is swung inwardly, as shown in Figure 3, the cam surface d^4 of the arm and the cam groove of the socket-end c^5 are out of alignment, the spring is put under compression, the arm d presses tightly against the end of the socket so as to form a frictional stop to prevent free swinging movement and the arm itself is pressed slightly out of its normal plane for the purpose of increasing frictional resistance at the upper end of the arm, as hereinafter described.

Since the center of the pivotal connection just described is the point through which the weight of the counter balance is applied to the sash and is projected inwardly from the inner surface of the sash to the plane of the vertical axes of the sash weights, the sash weights, although square in cross section, can be placed with their axes in a plane parallel with the sash without requiring the sash pulleys to be placed obliquely and without requiring the box to be made of unusual or abnormal depth. The sash chain b^x is connected by a T-headed, open-wire link b^2 to a stirrup b^3 which carries at its lower end a stud b^4 preferably rectangular in cross section as shown. The chain b^x , as shown, is wholly concealed within the box a , the stud b^4 projecting from within the box outwardly through the vertical slot a^7 in the plate a' . At its outer end the stud b^4 has secured to it a pivot plate b^5 .

The stud b^4 is by preference rigidly and permanently secured to the stirrup b^3 and to the pivot plate b^5 , preferably being welded therein in the usual manner. To the pivot plate b^5 is pivoted, as at b^6 , the swinging arm or link d , the latter preferably having double the thickness of the pivot plate b^5 and being recessed, as at d^5 , to receive the plate b^5 so that the faces of the plate b^5 and the arm d adjacent the box may be flush.

The counter balance or sash weight b is thus connected through the chain b^x , the stirrup b^3 , the stub b^4 , the plate b^5 with its pivot, and the link or arm d to the sash.

The arm d is also provided with a stud d^6 which projects toward the adjacent box and on the box is secured a locking plate e , which is slotted, as at e' , inwardly from the outer end of the plate, that is, the end toward the outside of the window and is thickened at its inner end. The plate e is so placed that the slot e' is in alignment with the stud d^6 of the arm d when the lower sash is in its lowest or closed position. Therefore as soon as the inward swinging movement of the sash is commenced, the stud d^6 , moving with the arm d , as shown in Figure 3, will enter the slot e' and will thereby hold the arm d from upward and downward movement. The upper member of the plate e , above the slot e' , is shorter than the lower member, so that it does not interfere with the upward movement of the stud d^6 when the sash is in a vertical position and in readiness to be moved upward. It will be observed that when the lower end of the arm d is thrust away from the sash by the above described cam action the upper end of the arm will be pressed toward the locking plate e and a frictional stop to restrain free movement of the parts will be created.

It is desirable to prevent the sash from being swung inwardly except when it is in its lowest position and for that purpose there is fixed to the box a stop a^8 , just above the level of the top of the sash c^2 , when the sash is in its lowest position, or, what is the same thing so far as the action of the stop is concerned, just above the level of some part which is fixed to the top rail of the sash and may be regarded as forming a part thereof. When the sash is in its lowest position the stop a^8 does not prevent the inward swinging of the sash, but as soon as the sash is raised from its lowest position the stop a^8 then prevents the inward movement of the sash and forms a guide for the sash during its upward movement.

To guide the sash in its continued upward movement there is mounted on the top rail of the sash a spring pressed bolt or latch f which is adapted to enter the vertical recess a^6 before mentioned and is provided with a knob f' . The latch prevents the inward swinging movement of the sash when it is in its lowest position and must be withdrawn by hand to permit such swinging movement and the knob f' furnishes a means whereby the latch can be withdrawn and at the same time the top of the sash can be pulled inward all in one operation.

At the bottom of the sash is secured a pin or roller c' which enters the vertical

recess α^6 and constitutes the pivot on which the sash is swung inward.

The advantages of the improved construction will be readily apparent without further explanation and it will also be understood that various changes in details of construction and arrangement can be made to suit different conditions of use without departing from the spirit of the invention 10 which is not limited to the particular construction shown except as pointed out in the accompanying claims.

I claim as my invention:

1. In a window, the combination of a 15 weight box having a vertical slot in its face plate, a sash, a sash weight traveling in the box, a sash chain located wholly within the box, a stud to which the chain is connected, said stud projecting through said slot, an 20 arm pivotally connected at one end to the sash and at the other end to said stud, and a horizontally slotted stop on the face plate of the box, the arm having between its ends a projection adapted to engage said stop, 25 whereby, when the sash is swung inwardly, the chain and the stud are held from swinging movement and the projection on the arm is brought into engagement with the stop.

2. In a window the combination of a 30 weight box, a sash, a sash weight, a sash chain, a socketed bracket secured to the sash, an arm pivotally connected at one end to the sash chain, a headed stud secured to

the arm at its other end and forming a pivotal connection with the socketed bracket 35 and a spring interposed between the head of the stud and the head of the socket, the socket and the arm being formed with co-operating cam surfaces whereby, when the sash is swung inwardly, the spring is placed 40 under compression and the arm is pressed tightly against the socket to form a frictional stop.

3. In a window the combination of a weight box, a sash, a sash weight, a sash 45 chain, a socketed bracket secured to the sash, an arm pivotally connected at one end to the sash chain, a headed stud secured to the arm at its other end and forming a pivotal connection with the socketed bracket, 50 a spring interposed between the head of the stud and the head of the socket, the arm also having at its other end a projection, and a slotted locking plate secured to the box for co-operation with the projection of 55 the arm, the socket and the arm having co-operating cam surfaces whereby when the sash is swung inwardly the spring is compressed, the arm is pressed tightly against the socket and the arm at its other end is 60 pressed against the locking plate for frictional contact therewith.

This specification signed this 11th day of October, A. D. 1921.

BERNARD HAUSMAN.
